UNITED STATES PATENT OFFICE.

JOHN L. CUMMINGS, OF MANSFIELD, PENNSYLVANIA.

BURGLAR-ALARM.

SPECIFICATION forming part of Letters Patent No. 622,037, dated March 28, 1899.

Application filed November 11, 1898. Serial No. 696,124. (No model.)

To all whom it may concern:

Be it known that I, JOHN L. CUMMINGS, a citizen of the United States, residing at Mansfield, in the county of Tioga and State of Pennsylvania, have invented certain new and useful Improvements in Burglar-Alarms; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention relates to that class of burglar-alarms especially adapted to be applied to windows and having wires arranged across the window, which are adapted to be disturbed by any one attempting to enter, and 20 thus sound an alarm.

The objects of the invention are to effect an alarm whether an attempt be made to raise the window or to enter through an opening made by cutting out a pane of glass, to effect an alarm whether the wires are pressed against or pulled or severed, to provide a device which can be used in connection with any special door-protector or general-alarm system, to provide a device in which the wires 25 may be readily disconnected during the day, so as to raise and lower the window in the usual manner, to provide an apparatus simple in construction and not liable to get out of order, but at the same time efficient and 30 sure in its action, and to secure other advantages and results, some of which may be referred to hereinafter in connection with the description of the working parts.

35 The invention consists in the improved burglar-alarm for windows, &c., and in the arrangements and combinations of parts of the same, all substantially as will be hereinafter set forth, and finally embraced in the clauses of the claim.

40 Referring to the accompanying drawings, in which like letters of reference indicate corresponding parts in each of the several views, Figure 1 is a perspective view showing a window upon which wires are arranged as 45 herein described, an alarm-box and circuit-wires leading therefrom to a suitable alarm-

bell and battery. Fig. 2 is a detail cross-sectional view showing the arrangement of one of the wires upon the window. Fig. 3 is a section of the alarm-box on line *x*, Fig. 4, 55 and Fig. 4 is an end view of the same on line *x'*, Fig. 3.

In said drawings, *a* indicates a window-frame, and *b b* the upper and lower sashes, 60 adapted to slide up and down in the usual manner. Wires *c* extend horizontally across the window, being suitably fastened at one end, as at *c'*, to the sash and running through guides *d d*, projecting from the sash, across 65 the panes to the opposite side, and from thence through other guides *d'* to an alarm-box *f*. Said guides may be small screw-eyes, hooks, pulleys, or anything similarly adapted to hold the wire in place and give it the proper direction.

The wires *c* are preferably very fine, so as not to be obtrusive and present an ungainly appearance.

At a convenient point near where the wires 75 leave the window-sash they are provided with coupling means *e*, permitting the portion upon the sash to be disconnected from the part on the window-frame, so that the sash may be raised and lowered, as usual, until it is desired to secure the window against tampering. When uncoupled, the ends do not pull back through the guides, because the openings in said guides are too small to permit the passage of the coupling members, and 80 thus the ends are always conveniently at hand for recoupling. Said coupling means may consist of the common device used on lockets and the like and comprising a spring member *e'*, adapted to enter a cylindrical 85 member *e''* and having a stop projection engaging an interior flange, as shown, or any other suitable means for detachably joining the ends of the wires may be used. If desired, the coupling members may be arranged 90 to pull apart under a strain a little less than is required to break the wire, so that if the window should be raised without uncoupling the members the wire will not be broken.

The alarm-box *f* comprises a casing *f'*, into 100 which extend the terminals *g g* of circuit-wires *g' g'*, shown in connection with a bat-

terry *h* and bell *h'* of any suitable construction. Said terminals are separated by a considerable space in the box *f*, so as to break the current, the ends preferably lying approximately parallel, as shown. Between said terminals *g g* of the circuit-wires is arranged a circuit-closer carrier *i*, pivoted upon a shaft *j*, extending across the box at right angles to the direction of the terminals. Said carrier comprises a frame *k*, pivoted upon the shaft *j* at two points, as at *l l*, and having on each side of the shaft arms *k'*, which project outwardly and upwardly from the shaft, as shown in Fig. 3. To the ends of each set of arms, which are preferably bent at right angles toward each other, is secured a U-shaped circuit-closer *m*, having downwardly-extending parallel arms *m'*, adapted to lie between and adjacent to the terminals *g g*. At their upper parts said arms *m'* are somewhat farther apart than the terminals; but their lower ends lie nearer together than said terminals and will pass therebetween. As the carrier lies in its normally horizontal position on the shaft *j*, the arms *m'* will not touch the terminals on either side, and the circuit will be interrupted or broken. When the carrier is tipped or oscillated in either direction, however, the arms of the circuit-closer on that side are forced downward between the terminals *g g* until their increasing width causes them to engage at their outer sides the inner sides of said terminals. The arms *m'* and wires *g g* are bared or provided with suitable contact-surfaces where they engage each other, and thus a continuous circuit may be completed through the circuit-closer *m*. At the same time the circuit is closed the movement of the arms is arrested and the circuit-closer carrier *i* is brought to a standstill, whereby the alarm will continue to sound until the carrier is again returned to its normal central position. The central portion of the U-shaped circuit-closer is laid against the inwardly-bent ends of the arms *k'* of the frame *k*, being suitably insulated against electrical contact therewith and fastened by wrapping *n*, soldering, or other appropriate means.

To effect oscillatory movement of the circuit-closer carrier *i*, I have arranged upon the shaft, inside of the frame *i*, independent pulleys *o o*, separated by washers *p* and each having a stud or arm *o'* projecting radially outward from its periphery. The wires *c* from the window are led into the box by means of suitable openings *q* and guides *d*, and each is passed over a pulley *o*, being fastened to the base of the stud *o'*. Beyond the pulley the wire passes downward through the bottom of the box, and to the end is attached a suitable weight or weights *r*. The stud or arm *o'* projects from the upper part of the pulley *o* out between the circuit-closers *m m*, being sufficiently long to engage said circuit-closers when the pulley is oscillated.

The weight *r* normally holds the wire *c* taut,

its length being adapted to cause the stud or arm *o'* to stand midway between the two circuit-closers *m m*. In this position the circuit-closer carrier *i* lies in its central position without closing the circuit on either side. If, however, any one of the wires *c* is pressed or pulled at right angles to its length, the pulley *o* is oscillated against the force of the weight *r* and the stud *o'* brought in contact with the circuit-closer *m* to force it downward and bring its arms into contact with the terminals *g g*, completing the circuit. On the other hand, if a wire be broken or cut, the weight will be released and allowed to fall, bringing the stud *o'* against the opposite circuit-closer *m* and forcing it between the wires *g g* to complete the circuit. The circuit-closer will normally retain its closing position and the bell or other alarm continue to sound until the circuit-closer is restored to its normal central position by hand upon the arrival of some person.

To prevent the weights from giving an alarm when the portion of a wire on the sash is disconnected from the part on the window-frame, I have provided a stay-rod *s* to be inserted in bearings in the sides of the box and hold the studs *o'* against being forced by the weights into engagement with the circuit-closer, as will be understood. This rod is withdrawn when it is desired that the apparatus shall be in complete working order.

It will be understood that any number of wires *c* may extend to the box *f* and that the pulleys in the box are suitably varied in number or construction to receive all said wires. I desire also to call attention to the fact that my device can be used in connection with any electrically-controlled door-protector or general system of burglar-alarm, the wires *g* being as well adapted to form a part of any circuit as to be connected to the battery *h* and bell *h'*, as shown.

Having thus described the invention, what I claim as new is—

1. In a burglar-alarm, the combination with a window-frame and a sash movable in said frame, of wires fastened to one side of said sash and extending across the panes, guides upon said sash and window-frame through which the wires run, coupling means arranged in said wire between the guides on the frame and those on the sash, and an alarm in connection with said wires and adapted to be operated by movement thereof or pressure against the wires, substantially as set forth.

2. In a burglar-alarm for windows, the combination with a battery, alarm and open circuit, of means for closing said circuit, wires stretched across the window-panes and made fast at one end to the sash and at the other end connecting with the circuit-closing means to operate the same, guides on the sash and window-frame through which said wires run and coupling means arranged in each wire between the adjacent guides at the edges of the sash and window-frame, said coupling

means being adapted to prevent withdrawal through the guides of the ends of the wire when uncoupled, substantially as set forth.

3. In a burglar-alarm, the combination with an open circuit, of a pivoted pulley having an arm projecting radially from the periphery, a wire passing over said pulley and made fast to the arm and extending beyond said arm, a weight attached to the end of said wire and a circuit-closer operated by said arm, substantially as set forth.

4. In a burglar-alarm for windows, the combination with an open circuit, of guides upon the window-sash, wires stretched across the panes of said window in said guides and fastened at one end, and leading to an alarm-box, pulleys pivoted in said alarm-box over which the wires pass, and weights attached to the free ends of said wires, arms projecting from the peripheries of said pulleys to which arms the wires are attached, and a circuit-closer adapted to be operated by said arms, substantially as set forth.

5. The combination with the wires *c*, and terminals *g*, of an alarm-box into which said terminals extend, pulleys pivoted therein over which said wires run, a circuit-closer carrier pivoted on the pulley-shaft and adapted to be operated by the oscillation of the pulleys, and

circuit-closers carried by said carrier and adapted to engage the terminals, substantially as set forth.

6. In a burglar-alarm system, the combination of pulleys independently pivoted upon a shaft and having radial arms, wires extending over said pulleys and having weights at their ends, a circuit-closer carrier pivoted upon the same shaft with said pulleys, a circuit-closer carried by said carrier, and circuit terminals adapted to be closed by said circuit-closer, substantially as set forth.

7. In a burglar-alarm, the combination of pulleys having radially-projecting arms, a circuit-closer carrier pivoted on the same shaft and having side frames adapted to be engaged by said arms as the pulleys oscillate, wires *c*, oscillating said pulleys, terminals *g*, *g*, and circuit-closers carried by said frames and adapted to be forced between said terminals to close the circuit, substantially as set forth.

In testimony that I claim the foregoing I have hereunto set my hand this 7th day of November, 1898.

JOHN L. CUMMINGS.
